MOVABLE ABUTMENT FOR CONTAINER
VEHICLES

Frederick W. Hankins, Philadelphia, and Frederick K. Fildes, Altoona, Pa.

Application August 10, 1933, Serial No. 684,483

8 Claims. (Cl. 105—366)

This invention relates to movable seating abutments for container vehicles, and more particularly to seat forming abutments or seating abutments adapted for engagement with the base portions

5 of containers and mounted for movement along the platform of the carrying vehicle in such manner as to afford adjustable stops for holding the containers against shifting.

One object of the invention is to provide in 10 a container vehicle, a series of abutments which define seats for one or more containers and which may be individually moved toward or away from the sides of the car to accommodate containers of varying width.

15 Another object of the invention is to provide trackways for guiding the movement of such abutments, the trackways extending along the top surface of the vehicle platform and over the side edges thereof, whereby the abutments may 20 be moved to positions in which they offer no obstruction to the lateral shifting of containers onto or off the vehicle.

Other objects and advantages characterizing 25 our invention will become more fully apparent from the description hereinafter set forth of one embodiment or example of the invention, having reference to the accompanying drawings, whereof:

30 Fig. I represents a part side elevation of a railway flat car fitted with container seating abutments of our invention.

Fig. II represents a cross section of the same, taken as indicated by the lines II—II of Fig. I, with certain of the parts broken away for clear- 35 ness of illustration.

Fig. III represents an enlarged plan view of one container seating abutment and surrounding portions of the railway car.

40 Fig. IV represents a cross section, taken as indicated by the lines IV—IV of Fig. III.

Fig. V represents a cross section, taken as indicated by the lines V—V of Fig. III.

Fig. VI represents a cross section, taken as indicated by the lines VI—VI of Fig. III.

45 Fig. VII represents a perspective view of one of the container seating abutments.

With reference to Fig. I of the drawings, the numeral 1 designates comprehensively a portion of a railroad flat car, and 2 the floor or platform thereof. At spaced intervals along the length of the car and at each side thereof, trackways are provided, constructed in the manner hereinafter described, and associated with each trackway there is a container seating abutment 3. The container seating abutments are movable indi-

vidually in a direction transverse to the longitudinal axis of the car a limited distance from the side sills 4 and collectively serve to define seats for containers of varying base dimensions.

Each trackway used for guiding the movement 5 of a container seating abutment 3, in the illus- trated example of our invention, is formed of a pair of Z-bars 5 inlaid in the car floor. The Z- bars 5 are disposed in opposite spaced relation

10 with their lower flanges 6 riveted to the under- frame of the car, and with their upper flanges 7 disposed in the plane of the top surface of the car platform and projecting towards each other. At their inner ends the Z-bars 5 are supported

15 on a longitudinal beam 8 comprising a part of the car under-frame, and at their outer ends the Z- bars 5 are supported upon the side sills 4. At- tached to the web of each side sill 4, there are ver- 20 tically extending Z-bar sections 9 which form continuations of the Z-bars 5, extending at right angles thereto downward along the side sills of the car. The Z-bar sections 9 have their outer

25 flanges 10 riveted to the side sills 4 and have their inner flanges 11 projecting towards each other at a spaced distance apart. The inner flanges 11 of the Z-bar sections 9 at their upper ends join the flanges 7 of the Z-bars 5, and at their lower ends are turned inward in a horizontal plane as indi- 30 cated at 12, to form a pocket which serves to pre- vent removal of the container seating abutments 3 from the car. At the inner ends of the Z-bars 5, adjacent to the longitudinal beams 8, the Z-bars 35 of each trackway are cross-connected by a yoke 15.

As most clearly shown in Fig. VII, the con- 35 tainer seating abutments 3 are in the form of castings of substantially T-shaped cross-section, having a central transversely extending portion 16 and having a longitudinally extending wall 17 which defines therewith two right angular pockets 40 for accommodating corners of two adjacent containers, such as represented at A in the drawings.

The central transversely extending portion 16 has inclined surfaces 18 at the top thereof, and the longitudinally extending wall 17 has an inclined sur- 45 face 19 at the top thereof, the inclined sur- faces 18, 19 serving to guide the base portion of a container A when lowered into the corner pock- 50 ets defined by the container seating abutments 3.

At its base each container seating abutment 3 is formed with oppositely projecting wings 20 which engage the undersides of the flanges 7 of the Z-bars 5 and the inner sides of the flanges 11 of the Z-bar sections 9, and which cooperate 55 with these parts to guide the movement of the

container seating abutment along the trackway. In an obvious manner each container seating abutment 3 may be readily moved inwardly or outwardly along the portion of the trackway 5 above the car platform 2, and when desired the container seating abutment may be moved over the side edge of the platform and downward to the position indicated in dot-and-dash lines in Fig. V. The wings 20, however, prevent a container seating abutment 3 from ever being completely detached from its trackway. At its longitudinally extending wall 17, as well as at the wall 21 of the central portion 16, each container seating abutment 3 is formed with key-hole slots 22 which are relatively wide near the 10 top and relatively narrow near the bottom. Moreover, at the base of each container seating abutment 3, there is formed a nut retaining pocket 23.

Associated with each trackway, there is provided a screw 24 which has an enlarged head 25 at its inner end in engagement with the yoke 15 which connects each pair of Z-bars 5. The screw 24 passes through and is fulcrumed on the 20 yoke 15, and in its normal position extends centrally between the Z-bars 5 just beneath the top surface of the car platform 2, see Fig. IV. Each screw 24 has thereon an elongated rectangular nut 26 engaging its threaded portion. Each 25 screw 24 at its outer end is of square or nut-shaped cross-section, as indicated at 27, so that it may be engaged by a socketed hand crank. Normally the nut 26 associated with the screw 24 fits snugly within the pocket 23 of the container seating abutment 3 and is so confined that 30 incident to the turning of the screw, the abutment will be progressed inwardly or outwardly along the trackway. However, the nut 26 may, when desired, be withdrawn from its pocket 23 with upward swinging of the screw 24, fulcruming on the yoke 15. By swinging the outer end 35 of the screw 24 in an upward direction, with removal of the nut 26 from its pocket 23, and by turning the nut 26 through an angle of 90°, so 40 that its long axis extends in a vertical direction, a container seating abutment 3 may be released from its screw 24, with the nut 26 passing through the keyhole slots 22 at their relatively wide portions. With a container seating abutment 3 45 has thus been released from its actuating screw 24, and passed over the end thereof, it may, in an obvious manner, be passed downward over the side sill 4 of the car to the position indicated in dot-and-dash lines in Fig. V.

The operation of the container seating abutments 3 will be apparent from the above description. It will be particularly noted, however, that by application of a socketed hand crank to the 50 actuating screw 24, the abutments 3 may be moved inwardly or outwardly so that they assume the desired positions for accommodating the base portions of the containers to be carried on the car, such positions depending upon the width of the containers. Inasmuch as the 55 screws 24 have threads of relative short pitch, each abutment 3 is in effect locked to the car except when its screw 24 is being rotated. Moreover, not only are the abutments 3 maintained rigidly in the desired position transversely of 60 the car, but by virtue of the engagement of their wings 20 with the Z-bars 5 they are effectively restrained against tipping to one side or the other in a direction longitudinal of the car.

Where containers are handled at large trans- 65 fer stations by means of overhead cranes, it is

not ordinarily necessary to change the positions of the container seating abutments 3, provided of course that all the containers being handled are of standard base dimensions. However, it frequently happens that containers have to be shifted onto or off railroad cars at wayside stations where large crane facilities are not available. With certain types of container transfer apparatus used at such wayside stations, including particularly apparatus in which hand-operated hoists are employed, it is desirable that the container seating abutments 3 be moved out of the way to facilitate the shifting of containers onto or off a car; and where the shifting is accomplished by such transfer apparatus, the seating abutments 3 are moved outwardly over the side edges of the car and downward along the side sills 4 to positions beneath the car platform 2. This enables the hoist operator to shift containers without having to raise and lower the containers more than a very short distance. For example, if it be desired to shift containers A from a railway car to an adjacent platform, the operator will first proceed to move all of the seating abutments 3 clear of the car platform 2. 25 Then each container may be raised only an inch or so by the hand-operated hoist preparatory to shifting it from the car to the adjoining platform. Furthermore, it will be readily seen that where no hoist facilities are available, by removal of the container seating abutments 3 to positions clear of the car platform 2 as shown in dot-and-dash lines in Fig. V, it is possible to manually shove a container onto or off the car without interference on the part of the container seating abutments. 30

While we have described one example of the practice of our invention, and have referred to one particular form of car construction which is desirably employed, it will be apparent that many changes may be made in the form of the trackways and container abutments herein described without departing from the spirit of our invention as defined in the annexed claims. 40

Having thus described our invention, we claim: 45

1. In a container carrying vehicle, a platform, a container seat forming abutment movable on said platform, means for guiding said abutment for travel along the top surface of the platform and over an edge thereof to a position beneath the top surface, and means whereby said abutment may be locked to the platform at varying distances from the edge thereof. 50

2. In a container carrying vehicle, a platform, a container seat forming abutment movable on said platform, means for guiding said abutment for travel along the top surface of the platform and over an edge thereof, and means whereby said abutment may be mechanically progressed along the platform and locked thereto at varying distances from the edge thereof. 55

3. In a container carrying vehicle, a platform, a container seat forming abutment movable on said platform, a trackway for guiding said abutment along the top surface of the platform and over an edge thereof to a position beneath the top surface, and a screw for moving said abutment along said trackway. 60

4. In a container carrying vehicle, a platform, side sills, and a container seat forming abutment movable on said platform, a trackway for guiding said abutment along the top surface of the platform transversely thereof to a side sill and then downward along the side sill to a position beneath 70

the platform, and a screw for moving said abutment along said trackway.

5. In a container carrying vehicle, a platform, a container seat forming abutment movable on said platform, a trackway inlaid in the platform and serving as a guide for said abutment, said trackway extending inwardly from the side edge of the platform and transversely thereof, a screw extending along said trackway, and a nut engaging the threads of said screw, said nut being normally connected to said abutment whereby turning of the screw will cause the abutment to be moved along the trackway, and said nut being adapted to be disconnected from said abutment 10 whereby the abutment may be moved beyond the side edge of the platform.

6. In a container carrying vehicle, a platform, a container seat forming abutment movable on said platform, a trackway for guiding said abutment for travel transversely along the platform to a side edge thereof, a screw fulcrumed on said platform and normally extending along said trackway, and a nut engaging the threads of said screw, said nut being normally connected to said abutment whereby turning of the screw will cause the abutment to be moved along the trackway, and said abutment having a keyhole slot through which said nut will pass when said screw is swung 15

about its fulcrum point, whereby the abutment may be moved beyond the side edge of the platform.

7. In a container carrying vehicle, a platform, a container seat forming abutment movable on said platform, said abutment defining corner seats for two adjacent containers and having wings projecting at opposite sides of its base, and a trackway on said platform formed of a pair of bars having flanges spaced apart and lying in the 10 plane of the top surface of the platform, said flanges engaging the top surfaces of the wings of said abutment and guiding said abutment for travel along the platform.

8. In a container carrying vehicle, a platform, a container seat forming abutment movable on said platform, said abutment defining a corner seat for a container and having wings projecting at opposite sides of its base, and a trackway on said platform formed of a pair of bars having flanges spaced apart and extending in the 15 plane of the top surface of the platform to a side edge thereof and then downward along the side of the vehicle, said flanges engaging the top surfaces of said wings and guiding said abutment 20 for travel along the platform and over the side edge thereof to a position beneath the platform.

FREDERICK W. HANKINS.

FREDERICK K. FILDES.
